WATER SYSTEM FOR PAPER WRAPPING MACHINES

Frank A. De Traglia, Utica, N. Y.

Application October 28, 1943, Serial No. 508,032

2 Claims. (Cl. 91—48)

My invention relates to a water system for paper wrapping machines and I declare the following to be a full, clear, concise and exact description thereof sufficient to enable anyone skilled in the art to which it appertains to make and use the same, reference being had to the accompanying drawings in which like reference characters refer to like parts throughout the specification.

The object of the invention is to provide a water system for paper wrapping machines which are used particularly for wrapping bread such as described and illustrated in patents to William A. Haysen, issued October 16, 1934, No. 1,977,307, issued Aug. 16, 1938, No. 2,127,028 and issued Dec. 3, 1935, No. 2,022,911.

Heretofore in paper wrapping machines the water used to moisten the paper to prevent it from buckling especially in hot weather, as it is fed into the machine was applied to the side of the paper that came next to the bread. This has been found harmful for the reason that it allows the water to come in contact with the bread and thereby causes a mold to form thereon after a very short interval. This mould renders the bread unfit for use.

The present invention avoids this harmful effect above mentioned by applying the water or moisture to the outside of the wrapper or to the side that does not come into contact with the bread.

The invention contemplates water cups located above the paper which allow drops of water to fall down upon a sponge that makes contact with certain pressure rollers employed to feed the paper into the machine.

The invention will be understood by referring to the drawings in which like characters refer to like parts throughout the specification.

Fig. 1 shows a perspective view of that portion of a paper wrapping machine that pertains to the present invention, parts being in section and parts broken away.

Fig. 2 is a detail enlarged view, showing a central vertical section, parts being in full, of a water cup and immediate parts that are employed in the machine.

Fig. 3 is a detail enlarged view showing a perspective of a lever used in connection with the water cup mentioned in Fig. 2.

Fig. 4 is a central vertical section of the view shown in Fig. 1, parts being in full and parts broken away.

Fig. 5 is a detail view showing a perspective of a sponge employed.

Fig. 6 is a detail view somewhat enlarged, showing a gear and ratchet, employed in the driving mechanism, parts being broken away.

Referring more particularly to the drawings only such parts of the bread wrapping machine are shown as pertain to the present invention. The machine embodies a frame 1 having horizontal bars 2, 2. Upstanding brackets 3, 3 are bolted at 4 or otherwise secured to the upper surfaces of bars 2, 2 opposite to each other. Each of the brackets has mounted to its top part a horizontally projecting shelf 5 bolted at 6 thereto. A trough 7 is secured to the under side of said horizontal shelves 5, 5 by welding or in any other suitable manner.

Five spaced transverse recesses or apertures 10 are made in the curved base 11 of trough 7 into which is fitted correspondingly shaped projecting parts 12 of sponge 13. Sponge 13 rests in trough 7 and its projecting parts 12 bear against the upper parts of the outer surfaces of five spaced cooperating pressure rollers 15 preferably made of rubber. Pressure rollers 15 are mounted to turn with rotatable shaft 16 which has bearings at either end in vertically sliding or floating bearing blocks 17, 17.

Each of the bearing blocks 17, 17 has on its opposite lateral sides ribs formed integral therewith that slide in corresponding grooves 18 made in the upstanding inner sides of brackets 3, 3.

The means for elevating bearing blocks 17, 17, whereby to relieve the pressure of rollers 15 against paper 20 and roller 21 therebeneath, hereinafter mentioned, contemplates a crank shaft 25 having bearings in elongated open recesses 26 made in the upstanding ends 27, 27 of the narrow plate 28. An elbow or handle 29 is formed at one end of shaft 25, whereby to aid in turning said shaft at will. Shaft 25 is offset at 27 to clear water cups 30 hereinafter described.

Narrow plate 28 is bolted to brackets 3, 3 by the same bolts 6, 6 that hold shelves 5, 5 in place on top of brackets 3, 3. Plate 28 is mounted on shelves 5, 5 a little off center thereof, whereby to aid also in clearing cups 30 from the offset portion 27 of shaft 25.

Journals 35, 35 are mounted above horizontal shelves 5, 5 to turn idly on shaft 25. A connecting rod 36 is screw mounted at its lower end to each of the vertically movable bearing blocks 17, 17 and at its upper end to a threaded aperture in the under surface of each of the journals 35, 35.

55 A coiled spring 40 is disposed about each of

the connecting rods 36, 36 between the upper surface of bearing block 17 and the under surface of shelf 5, whereby to exert a normal pressure downward against bearing block 17 to hold pressure rollers 15 against paper 20 and cooperating roller 21 therebeneath.

Rollers 41, 41 are mounted also on shaft 25 adjacent to journals 35, 35 and turn therewith. Each of the rollers 41 has a flat surface at 42 which is adapted to make contact with the upper horizontal flat surface of elevation 43 formed integral with the upper surface of shelf 5. Likewise collars 45, 45 are mounted on shaft 25 and turn therewith. They are located adjacent and on the opposite sides of journals 35, 35, and aid in holding journals 35, 35 in place.

Fig. 1 shows pressure rollers 15 in elevated position, whereby to relieve the pressure on paper 20 and roller 21 therebeneath. In order to lower said rollers 15 onto paper 20 and roller 21, crank handle 29 will be turned at right angles as shown in said Fig. 1. In this position the flat surfaces 42 of rollers 41 will rest upon the contiguous surfaces of elevations 43. In this position also coiled springs 40, 40 will force bearing blocks 17, 17 downward to lowermost position thereof, and, therefore, rollers 15 down onto paper 20 and roller 21, therebeneath.

Rollers 15 hereinabove mentioned are mounted to turn with shaft 16 which has bearings in blocks 17, 17, as above stated, whereas roller 21 therebeneath is mounted to turn with shaft 51 having bearings in the lower integral portions of brackets 3, 3. All of the rollers 15 and the roller 21 cooperate to move the paper 20 therebetween into the paper wrapping position within the machine, which movement is transverse to the feed of the bread, not shown.

The means for rotating said rollers 15 and 21 intermittently in opposite directions, whereby to feed the paper 20 contemplates spur gear 53 fixed to turn with the outer extended end of shaft 16. Spur gear 53 meshes with another spur gear 54 therebeneath fixed to turn with the extended part 55 of shaft 51. Shaft 16 has a further extension beyond the location of spur gear 53 to which is mounted to turn therewith a bevel gear 56 in mesh with another bevel gear 57 located on the same plane and fixed to turn with shaft 58 disposed at right angles to shaft 16 and having bearings in upstanding bearing brackets 59, 59.

The lower ends of said brackets 59, 59 are bolted or otherwise fastened to frame beam 60. Shaft 58 is held in place by boss 61 at one end and by hub 62 pinned at 63 to shaft 58 of beveled gear 56 at the other end. An elongated gear 65 is mounted on shaft 58 intermediate its bearings 59, 59. A pawl 66 fastened to the end of gear 65 and ratchet 67 fixed to turn with shaft 58 will cause an intermittent rotation of shaft 58. Shaft 58 forms the driving member through the gears and beveled gears aforementioned for feeding the paper 20 into the machine. Its loose mounting on shaft 58 with the aid of the ratchet 67 will cause the paper 20 to be fed into the machine when gear rack 69, hereinafter mentioned, moves downward but will not cause the paper 20 to be fed when said rack 69 moves upwardly. This intermittent rotation of shaft 58 will give sufficient time for each successive loaf of bread, not shown, to move in place in the machine for the wrapping thereof.

Gear rack 69 meshes with gear 65 and is mounted to have a sliding fit in angularly positioned guide 70. To this end it has lateral ribs 71, 71

which slide in complementary grooves in the contiguous sides of guide 70. Guide 70 is bolted at 72 or otherwise secured to member 73 which is bolted or welded to frame beam 60 at 74.

5 The lower part of rack 69 has an elongated slot at 75. An adjustable member 76 has a horizontal part that engages said part at the slot 75. A connecting rod 78 is pivoted at 79 to member 76. The opposite end of connecting rod 78 is pivoted to crank pin 79' of the adjustable block 80 mounted to slide in guide member 81 fastened to one of the spokes 82 of wheel 83, as shown in patent to Hayssen, issued Aug. 16, 1938, No. 2,127,028.

15 Wheel 83 is mounted to turn with power shaft 84 having bearings in frame 1. The rotation of wheel 83 will cause connecting rod 78 to reciprocate, whereby to exert an upward push and downward pull on rack 69. This in turn will cause the 20 rotation of gear 65 on the downward pull to rotate rollers 15 and roller 21 by means of the intermediate bevel gears 56, 55 and spur gears 53 and 54 as hereinbefore explained. This rotation of rollers 15 and 21, which is intermittent will 25 feed paper 20 into the machine for wrapping the bread.

30 The above mentioned wheel 83 and its immediate parts for actuating rollers 15 and roller 21 in an intermittent manner are described in patent to Hayssen, issued Aug. 16, 1938, No. 2,127,028, to which reference may be had for more particular description.

A roll of paper 90 used as an inside wrapper for the bread, not shown, is mounted on shaft 91 resting at either end in open bearings 92, 92 bolted at 93 to frame 1. Paper 90 is fed up under paper 20 as clearly shown in Fig. 1.

The novel means for applying moisture to the outside surface of paper 20, whereby it will serve 40 its purpose without coming in contact with the bread embodies said cups 30, five of which are shown although any number may be used to conform with the width of paper used. Each of the cups 30 has a flanged top closing member 101 and similar bottom closing member 102. A cylindrical glass casing 103 is mounted therebetween. Cork gaskets 104, 104 resting in said top and bottom members 101 and 102 respectively aid in sealing the container against leakage.

An elevated part 105 is formed on top member 101. It has a threaded throat part 106 for engaging the upper threaded part of hollow centrally disposed tube 107. A rotatable cover 108 is mounted to turn on elevated part 105. Its peripheral edge is knurled to aid in turning the same. Cover 108 has an aperture at 110 adapted to register with aperture 111 made in the horizontal upper surface of top member 101 when said cover 108 is turned to a predetermined position. A washer 112 is mounted on cover 108 about tube 107. Above washer 112 is a ring 115 which has an extension forming an upstanding flexible spring 116. The free end of spring 116 rests against the outer knurled surface of adjustable collar 117 to aid in holding it in place.

A lock nut 118 is threaded to the external threads of tube 107 above ring 115 to hold the parts below in place. Collar 117 has internal threads for screw mounting it to the upper end of tube 107. It has also a central aperture at 120 for the upward projection of the upper portion 121 of needle valve 123. The lower end of tube 107 is externally threaded to a nozzle 125 having a valve seat at 126 and tapering open passageway at 127. The outer surface of nozzle

125 is threaded for engaging and holding in place the bottom closing member 102.

A thimble or cylindrical member 130 is also screw mounted to the external threads of nozzle 125. The lower outer surface of cylinder 130 has external threads at 131 for engaging correspondingly threaded apertures made in narrow plate 28, whereby to hold said cups 30 in upright assembled position. A flat sided part 132 is formed externally on each of the cylinders 130 to aid in turning the same into its threaded apertures in plate 28. A narrow cylindrical passageway 135 is made in the central lower portion 136 of cylinder 130 for the passage of the water. The upper end of the passageway is funnel shaped at 137. An angular lead nozzle 138 is attached to the external threads 131, whereby to direct the water towards the central portion of the sponge 13.

The upper part 140 of thimble 130 has openings 141, 141 opposite each other which are closed by a glass cylinder 142 fitted within the interior of said cylinder 130.

The larger diameter 145 of needle valve 123 fits loosely within the tube 107. A shoulder 146 is formed on said needle valve 123 by reducing the upper portion in diameter. The lower end of a coiled spring 147 rests on said shoulder 146. Its upper end rests against the lower inner surface of adjustable collar 117, whereby said spring 147 will exert a pressure downward on needle valve 123 to hold it to its seat 126 or to adjusted position relative thereto.

The means for elevating needle valve 123 against the tension of spring 147 contemplates a forked lever 150 having a handle 151 to which the upper reduced angled part 121 is pivoted at 153. The free ends of lever 150 rest against the upper surface of adjustable collar 117 when acting as a lever. By tipping said lever 150 up into dotted line position illustrated in Fig. 4, needle valve 123 will be unseated. It can be adjusted to govern the amount of flow of water through passageway 135 by turning collar 117 to the right or left. Spring 116 will hold it in adjusted position. An aperture 155 is made in the side of tube 107 adjacent its lower end, whereby to admit water from cup 30 therein.

In operation the user of the machine will first fill cups 30 with water. This can be done by turning covers 108 to bring apertures 110 to register with apertures 111 in member 101. Needle valve 123 can be adjusted to govern the amount of water flowing from cups 30 by turning collar 117 to a predetermined position. They will be lowered then towards their seats 126, by actu-

ating levers 150 to full line position illustrated in Figs. 2 and 4.

Rollers 15 will be lowered against paper 20, paper 90 therebeneath and roller 21 under both by turning crank handle 29 in the arc shown by dotted lines shown in Fig. 1.

The motor power, not shown, will turn wheel 83 to actuate gear rack 66, whereby to turn gear 65 and shaft 57 intermittently. Shaft 57 in turn will rotate rollers 15 and roller 21 through the medium of bevel gears 51, 56 and spur gears 53 and 54 as above explained.

The water from cups 30 will drip on to sponge 13 which will dampen the outer surfaces of roller 15 that come into contact with the outer surface of paper 20. The paper thus dampened on its outer side will move into the machine without crimping or buckling and without dampening the bread, not shown.

20 Rolls of paper 20 and 90 can be replaced easily from time to time by setting new rolls into their respective bearings. Likewise the free ends of paper 20 and 90 can be fed easily in between rollers 15 and 21 when found necessary.

25 Having thus described my invention what I claim as new and desire to secure by Letters Patent is:

1. In a water system for paper wrapping machines, a roller to aid in moving said paper through the machine, pressure rollers cooperating with said first named roller to move said paper through the machine, a trough mounted in said machine, apertures made in the base of said trough, sponges mounted in said trough and projecting through said apertures, said sponges contacting with said pressure rollers, cups mounted above said trough for supplying water to the sponges therein, and needle valves mounted in said cups to govern the flow of water therefrom.

40 2. In a water system for paper wrapping machines, a roller to aid in moving said paper through the machine, pressure rollers cooperating with said first named roller to move said paper through the machine, a shaft for supporting said pressure rollers, bearing blocks for supporting said pressure roller shaft, sponges mounted to contact said pressure rollers, cups for supplying water to said sponges, a crank shaft carried by said machine, rollers having flat surfaces carried by said crank shaft, journals mounted to rotate freely on said crank shaft, and rods connecting said bearing blocks with said journals, whereby the turning of said crank shaft will relieve the pressure of said pressure rollers on the paper.

FRANK A. DE TRAGLIA
